 Quilted specimen, admitted prior art, no date given.

Primary Examiner—Robert M. Spear*Attorney, Agent, or Firm*—Finnegan, Henderson, Farabow, Garrett & Dunner, L.L.P.[57] CLAIM

I claim the ornamental design for pattern for a paper product, as shown and described.

DESCRIPTION

The solo FIGURE is a top plan view of a pattern for a paper product showing my new design.

The broken lines in the drawing depict the boundaries of the claimed design as well as the boundaries of the paper product to which the pattern is applied and form no part of the claimed design.
